US00D968985S

(12) **United States Design Patent** (10) Patent No.: **US D968,985 S**
(45) Date of Patent: **** Nov. 8, 2022**

(54) **SPRING FOR TAPE MEASURE HOLDER**

(71) Applicant: **Jun Young Choi**, Seoul (KR)

(72) Inventor: **Jun Young Choi**, Seoul (KR)

(**) Term: **15 Years**

(21) Appl. No.: **35/512,240**

(22) Filed: **Jan. 20, 2021**

(80) **Hague Agreement Data**

Int. Filing Date: **Jan. 20, 2021**

Int. Reg. No.: **DM/214715**

Int. Reg. Date: **Jan. 20, 2021**

Int. Reg. Pub. Date: **Jul. 23, 2021**

(30) **Foreign Application Priority Data**

Jul. 31, 2020 (KR) 30-2020-0035667

(51) **LOC (13) Cl.** **10-04**

(52) **U.S. Cl.**

USPC **D10/74**

(58) **Field of Classification Search**

USPC D10/70, 71, 74
